UNITED STATES PATENT OFFICE

152,342

DESIGN FOR A HELICOPTER

Harold E. Lemont, Jr., East Providence, R. I., assignor to Helicopter Engineering and Construction Corporation, a corporation of Rhode Island

Application January 27, 1947, Serial No. 136,455

Term of patent 3½ years

(Cl. D71—1)

To all whom it may concern:

Be it known that I, Harold E. Lemont, Jr., a citizen of the United States of America, residing at East Providence, county of Providence, State of Rhode Island, have invented a new, original, and ornamental Design for a Helicopter, of which the following is a specification, reference being had to the accompanying drawing, forming a part thereof.

Figure 1 is a front end view showing my new design of helicopter;

Figure 2 is a top plan view; and

Figure 3 is a side elevation thereof.

Each side of the helicopter is substantially the same.

I claim:

The ornamental design for a helicopter, substantially as shown and described.

HAROLD E. LEMONT, JR.
